UNITED STATES PATENT OFFICE.

GEORGE B. HAINES, OF CHICAGO, ILLINOIS, ASSIGNOR OF ONE-HALF TO
ROBERT J. GUNNING, OF SAME PLACE.

CAR-STARTER.

SPECIFICATION forming part of Letters Patent No. 352,126, dated November 9, 1886.

Application filed April 6, 1886. Serial No. 197,933. (No model.)

To all whom it may concern:

Be it known that I, GEORGE B. HAINES, a citizen of the United States, residing at Chicago, Illinois, have invented certain new and useful Improvements in Car-Starters, of which the following is a specification.

The object of my invention is to make a car-starter that can be used with equal advantage and facility as the car is moved in one direction or the other; and my invention consists in the features and details of construction hereinafter described and claimed.

In the accompanying drawings, Figure 1 is a plan view of the bottom of a car containing my improvements, with a double ratchet-wheel on each axle; Fig. 2, a side elevation of the car; Fig. 3, a longitudinal vertical sectional view of the car, showing a single ratchet-wheel on each axle; Fig. 4, an end view of the car, showing the slot for the draw-bar; Fig. 5, an enlarged perspective of the joint or connection between the draw-bar and the car-starter; Fig. 6, an end view of the brace, support, or guide for the car-starter back of its connection with the draw-bar; and Fig. 7 an enlarged view of a sliding weight for holding the pawl out of engagement with the ratchet when passing back to its normal position.

In the drawings, A is the bottom of the car; B, the sills or bottom frame-work; C, the axles; D, the ratchet-wheels on such axles; E, the pawl engaging with teeth of the ratchet; F, an end-wise movable bar to which the pawls are pivoted, and to the end of which the draw-bar is attached; G, the draw-bar; H, a strap or piece attached to the under side of the end sills of the car to form a slot through which the draw-bar passes, and in which it may have lateral play; J, braces attached to the axle boxes or axles, and passing around in front of the wheels for the purpose of supporting and guiding the bars F; K, a sliding weight; L, the joint connecting the draw-bar G and the starter-bar F; and M a spring on the draw-bar.

In making a car with my improved starter, I take any car, street or railway, of ordinary construction, and place ratchet-wheels on its axle at any convenient point between the wheels. I prefer to use two of these ratchets on each axle, although this is not necessary.

Where two ratchet-wheels are employed, I would recommend that they be cast on one hub and sufficiently close together to make this convenient. The diameter of the ratchet-wheels should be as large as the position in which they are to be used will admit of, as the larger the ratchet-wheel the greater will be the leverage or pressure secured. The ratchet-wheel should be rigidly attached by a set-screw, spline, or other convenient means to the axle, so as to revolve with it.

After providing the axles with ratchet-wheels, as above described, I arrange a starter-bar in place, preferably just under the floor of the car. This starter-bar is preferably slotted, and the ratchet-teeth allowed to pass up into or through the slot.

To hold the starter-bar in place, I attach straps or bars to the axle-boxes or to the axle, as may be found most convenient, and bring them around in front of the wheels and across the bottom of the car to a proper height to support and guide the starter-bar. These supporting straps may be made in several pieces, as shown in Fig. 1, or in one continuous piece properly bent to meet the requirements of that feature, and they should be provided with slots or openings, as shown in Fig. 6, to permit the starter-bars to pass through and be properly supported and guided.

One end of the starter-bar is attached to the draw-bar by means of a universal joint, preferably like that shown in Fig. 5, so that as it is raised or lowered with the car-body, or moved toward one side or the other, it will freely move in the joint without disturbing the position, relations, or functions of the starter-bar and its connections.

Where two ratchet-wheels are employed on the same axle, they should have their ratchets in reverse directions, and two starter-bars should be employed with their opposite ends connected with the draw-bars, so that the car can be started and drawn in either direction with equal facility. This construction is clearly shown in Fig. 1.

Attached to the starter-bars are pawls adapted to engage with the teeth of the ratchet, each preferably provided with an end portion extending beyond its pivotal point. This end or

piece extends under a vertically - movable weight suspended on a bolt from the bottom of the car or held in place by guides or other convenient means. As the bar is drawn toward this 5 movable weight, the free end of the pawl will pass under it, and, owing to the engagement of its pawl end with the teeth of the ratchet, will lift the movable weight as it passes under it; but the instant the tension is released the 10 weight will be heavy enough to lift the pawl end out of engagement and permit it to be carried back to its normal position clear of the ratchet-teeth.

The draw-bar should be provided with a 15 spring or other means to carry it back, and with it the starter-bar, to its normal position. This spring, as shown in the drawings, is made as a spiral spring surrounding the draw-bar, and one of its ends rests against the end sill 20 of the car and the other against a shoulder or rest that is movable backward or forward with the movements of the draw-bar or starter-bars. The object of this spring being to throw or move the car-starter back to its normal position after its function is performed, so that it 25 will be ready for another operation when required, it may be made and applied in any convenient way to accomplish this object.

In Fig. 3 I have shown a modification of my 30 invention. As there represented, it consists in a single ratchet-wheel on the front and rear axles of the cars. The starter-bars only extend back enough beyond the ratchet to permit of its forward and backward play, and 35 each starter-bar is separate from and independent of the other, and the two starter-bars have no connection with each other. The ratchet-wheels are reversed, so that one will be engaged with its appropriate pawl and operated 40 upon when the car is drawn in one direction,

while the other will be engaged with its pawl and operated upon when the car is drawn in the opposite direction. In this way the same result is secured as where the ratchet-wheels are used in pairs, as above described, while a 45 less number of parts are employed and the construction simplified. This construction is particularly applicable to lighter cars where its greater economy will be appreciated.

What I regard as new, and desire to secure 50 by Letters Patent, is—

1. In a car-starter, a starter-bar adapted to have a vertical and an endwise movement independent of the movements of the car proper, in combination with means for supporting and 55 guiding the same, substantially as described.

2. In a car - starter, the combination of a starter-bar and a draw-bar secured together by a universal joint in front of the car-axle, whereby the draw-bar may be moved freely 60 up and down and sidewise, substantially as described.

3. In a car-starter, the combination of a starter-bar, guides for the starter-bar wherein the same moves, and braces or supports for 65 such guides secured on the axles or axle-boxes, whereby the car-starter may be moved independently of the body of the car, substantially as described.

4. In a car-starter, the combination of a 70 vertically-adjustable weight with the free end of a pivoted pawl, substantially as described.

5. The combination, with a car, of a draw-bar secured by a universal joint in front of the axle, permitting it to be moved vertically 75 and laterally, substantially as described.

GEORGE B. HAINES.
